ABSTRACT OF THE DISCLOSURE

A method of relieving pain in mammalian patients comprising administering a therapeutically effective amount of 5,5-dimethyl - 10 - hydroxy-8-(3-methyl-2-octyl)-2-(2-propynyl) - 1,2,3,4 - tetrahydro - 5H - [1]benzopyrano[3,4-d]pyridine to a patient.

DETAILED DESCRIPTION OF THE INVENTION

This invention relates to a method of relieving pain using 5,5-dimethyl-10-hydroxy-8-(3-methyl-2-octyl)-2-(2-propynyl) - 1,2,3,4 - tetrahydro - 5H - [1]benzopyrano[3,4-d]pyridine as the analgesic agent.

While there are a number of currently available analgesic agents on the market, the search for improved analgesic agents has been continued, since a number of the more potent agents are classified as narcotics. That is, if it is necessary for patients to take analgesic agents such as codeine, morphine and the like over a prolonged period of time, the addiction liability is high. The present invention provides an analgesic agent which appears to be free from addiction liability.

5,5 - dimethyl - 10 - hydroxy-8-(3-methyl-2-octyl)-2-(2-propynyl) - 1,2,3,4 - tetrahydro - 5H - [1]benzopyrano[3,4-d]pyridine has previously been reported to be useful as a central nervous system depressant (see U.S. Pat. No. 3,576,798). It has now been found that the compound possesses analgesic activity.

The compound useful in the practice of this invention is represented by the formula

The compound can be prepared according to the method taught in U.S. Pat. No. 3,576,798.

In the practice of this invention, 5,5-dimethyl-10-hydroxy-8-(3-methyl - 2 - octyl) - 2 - (2-propynyl)-1,2,3,4-tetrahydro-5H-[1]benzopyrano[3,4-d]pyridine is administered to mammalian patients suffering from pain in dosages of from 0.01 to 0.2 mg./kg. I.V. and from 2.5 to 40 mg./kg. p.o., preferably in divided doses, i.e., three to four times daily.

The analgesic activity of the compound was evaluated in the hot plate analgesic test, the acetic acid writhing test and the rat tail flick study.

In the hot plate analgesic test carried out according to the method of Woolfe, G. and MacDonald, A. D., J. Pharmacol. Exper. Therap., 80, 300 (1944), 5,5-dimethyl-10-hydroxy-8-(3-methyl-2-octyl) - 2 - (2 - propynyl)-1,2,3,4-tetrahydro-5H-[1]benzopyrano[3,4-d]pyridine has an I.V. ED₅₀ of 0.16 mg./kg. (95% C.L.=0.11 to 0.20) and an oral ED₅₀ of 7.7 mg./kg. (95% C.L.=4.1 to 12.7).

2

[Morphine exhibits an intravenous ED₅₀ value in mice of 0.009 mg./kg. (95% C.L.=0.006 to 0.014) and an oral ED₅₀ value of 12.6 mg./kg. (95% C.L.=9.7 to 16.4)].

Analgesic activity was also evaluated via the acetic acid writhing method, modified from that described by Whittle Brit. J. Pharmacol., 22, 296 (1964). The number of writhes were counted for a 20 minute period beginning 5 minutes after the injection of the acid. Analgetic potency was calculated from the difference between the test groups and their controls. The compound exhibits an intravenous ED₅₀ value of 0.03 mg./kg. (95% C.L.=0.02 to 0.04) and an oral ED₅₀ value of 4.3 mg./kg. (95% C.L.=3.2 to 5.9).

The analgesic activity of the compound useful in the practice of this invention in the acetic acid writhing test is summarized in the following tables:

TABLE I

Acetic acid writhing test in mice (I.V.)

	Dose mg./kg. p.o.:	Percent inhibition
20	0.01	5.8
	0.02	24.5
	0.023	39.6
	0.03	80.0
25	0.06	86.4
	0.13	100.0

ED₅₀=0.03 mg./kg. (95% C.L.=0.02 to 0.04) I.V.

TABLE II

Acetic acid writhing test in mice (oral)

	Dose mg./kg. p.o.:	Percent inhibition
30	1.0	17.5
	2.5	40.6
	5.0	47.0
35	7.5	62.6
	10.0	72.5

ED₅₀=4.3 mg./kg. 95% C.L.=3.2 to 5.9) p.o.

The oral ED₅₀ of codeine phosphate is 15.6 mg./kg. (95% C.L.=9 to 23).

Analgesic activity was also exhibited in the rat tail flick study (D'Amour and Smith, J. Pharmacol. Exper. Therap., 72: 74, 1941). The compound exhibits an intravenous ED₅₀ value of 0.13 (95% C.L.=0.07 to 0.18) and an oral ED₅₀ value of 13.8 mg./kg. (95% C.L.=4.5 to 23.9).

The compound useful in the practice of this invention can be formulated into various pharmaceutically acceptable dosage forms such as tablets, capsules, pills and the like for immediate or sustained release, by combining the compound with a suitable pharmaceutically acceptable carrier or diluent according to methods well known in the art. Such dosage forms may additionally include lubricants, excipients, binders, fillers, flavoring and sweetening agents and other therapeutically inert ingredients necessary for the formulation of the desired preparation.

We claim:

1. A method of relieving pain in a mammalian patient suffering therefrom comprising administering to said patient a therapeutically effective amount of 5,5-dimethyl-10-hydroxy-8-(3-methyl-2-octyl) - 2 - (2-propynyl)-1,2,3,4-tetrahydro-5H-[1]benzopyrano[3,4-d]pyridine.

2. The method of claim 1 wherein said compound is administered in dosages of from 0.01 to 40 mg./kg. of body weight daily.
